(57) **CLAIM**

The ornamental design for a set of Christmas tree quick
plugs, as shown and described.

DESCRIPTION

FIG. 1 is a perspective view of one plug from a set of the
Christmas tree quick plugs shown separately for completeness
of illustration showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right-side elevational view thereof;

FIG. 7 is a top plan view thereof;

FIG. 8 is a bottom plan view thereof;

FIG. 9 is a perspective view of a second plug from a set of
Christmas tree quick plugs shown separately for completeness
of illustration showing my new design;

FIG. 10 is another perspective view thereof;

FIG. 11 is a front elevational view thereof;

FIG. 12 is a rear elevational view thereof;

FIG. 13 is a left side elevational view thereof;

FIG. 14 is a right-side elevational view thereof;

FIG. 15 is a top plan view thereof;

FIG. 16 is a bottom plan view thereof;

FIG. 17 is a perspective view of a third plug from a set of
the Christmas tree quick plugs shown separately for completeness
of illustration showing my new design;

FIG. 18 is another perspective view thereof;

FIG. 19 is a front elevational view thereof;

FIG. 20 is a rear elevational view thereof;

FIG. 21 is a left side elevational view thereof;

FIG. 22 is a right-side elevational view thereof;

FIG. 23 is a top plan view thereof;

FIG. 24 is a bottom plan view thereof;

FIG. 25 is an assembled view of thereof;

FIG. 26 a partial enlarged view of portion 26 in FIG. 17;

FIG. 27 is a partial enlarged view of portion 27 in FIG. 18;
and,

FIG. 28 is a perspective view of the complete set of
Christmas tree quick plugs showing my new design in its
entirety.

The broken lines shown in the drawings represent portions
of the set of Christmas tree quick plugs which form no part
of the claimed design. The dot-dash style broken lines
represent boundary lines and form no part of the claimed
design.

1 Claim, 28 Drawing Sheets
